UNITED STATES PATENT OFFICE

JOHN STANLEY STULL, OF CHICAGO, ILLINOIS, ASSIGNOR TO WESTERN ELECTRIC COMPANY, INCORPORATED, OF NEW YORK, N. Y., A CORPORATION OF NEW YORK

THREADING DIE

Application filed January 5, 1929. Serial No. 330,587.

This invention relates to dies, and more particularly to adjustable threading dies.

In threading metal parts it is desirable to use a die having sections which are easily and readily replaceable. It is also desirable that such sections be adjusted with a minimum of effort and that they be efficient in operation.

It is an object of the present invention to provide a simple and efficient die, wherein the parts may be produced economically and readily assembled and disassembled.

In order to accomplish this and other objects, there is provided in accordance with the general features of the invention in one embodiment thereof an adjustable threading die having a die head member with a conical end provided with three radial slots for receiving rectangular chasers or threading members, the threaded portions of which are parallel with the axis of the head and the opposite ends of which abut a flared adjusting ring threaded upon the head and receiving an inwardly threaded cap securing the chasers in position in the slots. Resilient projections of a tubular spring member abut against the threaded ends of the chasers and hold them in position against the flared adjusting ring while the threaded cap is being tightened.

A clear understanding of the invention will be had from the following description of one specific embodiment thereof when taken in connection with the accompanying drawings, wherein

Fig. 1 is a longitudinal, sectional view of the adjustable die;

Fig. 2 is an end view of the die;

Fig. 3 is an enlarged vertical, sectional view of an adjusting ring for the die;

Fig. 4 is an enlarged perspective view of a horseshoe-shaped locking member for the adjusting ring of Fig. 3, and

Fig. 5 is an enlarged perspective view of a

resilient tubular member for retaining the chasers of the die in position.

Referring now to the drawings in which like numerals designate similar parts throughout the several figures there is shown a body portion 10 of the adjustable die which is secured in operative position by a conventional structure shown in dotted outline and designated generally by the numeral 11. The die structure consists of a tubular die 55 retaining head 13 having a conical face 14 which is provided with three correspondingly sloped slots 15 for receiving chasers. The die retaining head 13 has a central cylindrical aperture 16 extending lengthwise of the tool 60 and connecting with a transverse aperture 17 (Fig. 1) for providing an outlet for the chips falling from the chasers, and in the cylindrical aperture 16 there is frictionally positioned a tubular spring member 18 (Fig. 65) which has forwardly projecting resilient portions 19 that extend slightly into the spaces adjoining the slots 15 for receiving the chasers.

Chasers or threading members 20 each provided with a shoulder portion 22 (Fig. 1) and a rectangular shank portion 23 are slidably positioned within the slots 15 with the shoulder portions 22 engaging the ends of the resilient portions 19 of the tubular spring 75 member 18 so as to resiliently prevent the chasers from moving towards the center of the tool. An adjusting ring 24 (Fig. 3) having inner threads 25 cooperating with outer threads 26 on the tubular die retaining head 13 has a flared inner surface 27 which abuts against the ends of the shanks 23 of the chasers 20 and is adapted to force the chasers 20 inwardly against the resisting force of the resilient projections 19 upon the actuation of 85 the flared adjusting ring 24 toward the left (Fig. 1) over the die retaining head 13.

An annular cap member 30 provided with inner threads 31 for cooperating with outer threads 32 on the adjusting ring 24 has a 90

flange portion 33 which is adapted to abut against the outer surfaces of the chaser shanks 23 and force them against the conical face 14 of the retaining head 13 when the 5 cap is screwed down to secure the chaser 20 within the slots in whatever position they are adjusted to by the ring 24. In order to lock the ring 24 in the position to which it is adjusted there is provided a slot 34 in the right 10 hand end (Figs. 1 and 3) of the adjusting ring 24 for receiving a horseshoe-shaped member 35, and there is also a collar 36 having inner threads 37 cooperating with outer threads 38 on the adjusting ring 24. When 15 the collar 36 is turned against the horseshoe-shaped member 35 inserted within the slot 34 the threaded right hand end (Figs. 1 and 3) of the adjusting ring 24 is flexed sufficiently to cause it to bind against the right hand 20 end portion of the threads 26 of the tubular die retaining head 12 to lock the flared adjusting ring 24 in position.

In the operation of the structure the flared adjusting ring 24 is rotated about the threads 25 26 of the tubular die retaining head 13 to move the threading members or chasers 20 inwardly within the sloping, retaining slots 15 against the resilient opposing force of the projections 19 of the tubular spring member 30 35 18 to adjust the chasers to whatever size thread it is desired to cut; and the annular cap member 30 is then tightened to secure the chasers in this position. The adjusting ring 24 is now locked in position by turning the threaded collar 36 against the horseshoe-shaped member 35 to bind the right hand threaded end of the adjusting ring against the threads 26 of the die retaining head 13, and the die is then ready for threading parts. 40 When it is desired to remove the chasers 20 for sharpening or replacement it is apparent that this may be readily accomplished by unscrewing the annular cap member 30, and the chasers to be replaced are then easily inserted 45 within the slots 15 between the spring projections 19 and the flared adjusting ring 24.

Thus it is believed to be clear that the improved die is one in which the parts may be 50 readily replaced and adjusted in accordance with the object of the invention. By constructing the die of a number of identical chasers, the chasers may be economically manufactured in quantities and in the event that any of them become defective they may be easily interchanged. Of course, it is to be understood that the invention is not to be limited to the specific structure here described and illustrated, but is to be limited only by 55 the scope of the appended claims.

What is claimed is:

1. In a threading die, a die head, a plurality of chasers supported therein, a ring member threaded upon the head for adjusting 60 the chasers and having a slot, a horse-

shoe-shaped member insertible within the slot, and a collar threaded to the ring member for abutting against the horseshoe-shaped member to bind one end of the ring member to the die head to lock the ring member in 70 position.

2. In a threading die, a die head, a plurality of chasers mounted radially of the die head, a chaser adjusting member with a flared inner end surface threaded to the die head 75 having two sets of external threads, a cap member for securing the chasers in the die head engaging one set of the threads, and means comprising a ring member and a collar for locking the chaser adjusting member 80 in position engaging the other set of threads.

3. In a threading die, a die head, a plurality of chasers mounted radially of the die head, a ring member with a flared inner end surface threaded to the die head for adjusting 85 the chasers and having two sets of external threads and a slot, a cap member for securing the chasers to the die head engaging one set of the threads, a collar engaging the other set of threads, and a horseshoe shaped 90 member mounted within the slot and cooperating with the collar for locking the ring member in fixed position.

4. In a threading die, a die head provided 95 with a conical end surface having radial recesses and a central cavity, die members mounted within the recesses, a cap member having an inner beveled surface for retaining the die members within the recesses, a ring member threaded upon the die head and having an inner end flared surface for adjusting 100 the die members, the cap member being threaded to the ring member, and a resilient member with a tubular body portion and rectangular projections extending outwardly 105 therefrom positioned within the central cavity of the die head for pressing against the inner ends of the die members.

5. In an adjustable threading die, a die head provided with a central cavity and a 110 conical end surface having rectangular recesses, chasers inserted within the recesses, a ring member with an inner flared end surface for adjusting the chasers threaded to the die head and provided with a slot, a cap member provided with an inner beveled surface threaded to the ring member for retaining the chasers within the recesses, a horseshoe shaped member inserted within the slot of the ring member for locking it in position, a collar threaded to the ring member and abutting against the horseshoe shaped member to effect the locking position, and a resilient member having a tubular body portion and rectangular end projections cooperating 120 with the chasers inserted within the central cavity of the die head for preventing inward movement of the chasers.

6. A threading die comprising a radially 130 slotted die head, a plurality of chasers ra-

dially movable in the slots, a ring member
threaded on said head and having a flared
inner surface engaging the outer portions
of the chasers and having a flexible portion
5 also threaded on the die head, means for
flexing the flexible portion to lock the ring
member in fixed position relative to the die
head, and releasable means cooperating with
the ring member to secure the chasers in fixed
10 positions relative to the die head.

In witness whereof, I hereunto subscribe
my name this 24th day of December, A. D.
1928.

JOHN STANLEY STULL.
